PIPE FORMING PROCESS

Winford L. Enghauser, Lebanon, Ohio

Application October 25, 1933, Serial No. 695,155

2 Claims. (Cl. 78—94)

This invention relates to the art of forming pipe, and is particularly directed to a method for joining the longitudinally abutting edges of formed-up flat pipe stock.

5 It is the object of this invention to provide a method for forming pipe from flat stock wherein the longitudinal joint of the formed pipe is closed or seamed by frictionally inducing a metal forming heat in the metal of adjacent longitudinal seam flanges and controlling the flow of the metal so that the flanges merge together and become fused resulting to constitute a seam in a pipe having no apparent joint, or in other words, of continuous unbroken circular structure.

10 It is a further object of the invention to provide a method for closing the longitudinal joint of rolled-up pipe stock in which apparatus is included for preserving the roundness of the pipe during the joint forming operation.

Other objects and further advantages will be more fully apparent from a description of the accompanying drawing, in which:

Figure 1 is a side elevation of a pipe forming apparatus including the present improved apparatus and employing the present method.

Figure 2 is a perspective view of Figure 1, showing the formation of the pipe as it passes through the apparatus.

Figure 3 is a sectional view taken transversely of the mandrel and supported pipe prior to the joint forming operation.

Figure 4 is a sectional view taken transversely of the pipe, the pipe supporting means, and the joint forming disc, showing the pipe in finished or joined condition.

Figure 5 is a sectional view on line 5—5, Figure 4, illustrating in detail the action of the forming discs on the adjacent longitudinal seam flanges of the pipe.

40 The improvements concerned in this application have been illustrated in conjunction with machinery for forming up a tube and bringing together longitudinally related flanged edges for operation thereon by the particular mechanism concerned in this invention. For the purpose of identification, the joint sealing or forming unit concerned herein is generally designated at 6.

45 Referring more specifically to the drawing, a table or frame 7 is employed. The stock from which the pipe is formed is supplied in a flat strip 8 and is fed initially to the apparatus for rolling the strip by lateral contact into a tube and bringing the longitudinal edges of the strip into proximity. For this purpose rollers 9 are pro-

vided, the rollers having arcuate tracking grooves.

In the present illustration there are three pairs of rollers. The rollers of each pair are spaced apart for receiving the metal strip between them. These rollers are journaled on vertical axes and are driven by power through gears 9a. Initially the sheet is forced between these rollers by means of power driven rollers 10, 10 engaging the top and bottom of the strip.

10 The strip 8 is moved toward a mandrel 11. This mandrel is supported at its end adjacent the feeding end of the machine by means of a plate extension 12 disposed upwardly and bolted to an arm 13 of the frame. The metal is rolled up from 15 the sides and is brought together after it passes the support of the mandrel. The mandrel extends to a position adjacent the seaming or joint forming apparatus. The last rollers of the series accordingly engage against the completely rounded 20 pipe structure, bringing it together in perfectly circular shape about the mandrel. The formed pipe slips along the mandrel and passes between the rollers of the joint forming mechanism.

25 The rollers 9 are driven at a low rate of speed. The speed of these rollers is made to conform to the rate of lineal travel of the pipe so that there is no friction taking place in the feed, the movement of the rollers merely aiding the lineal feed of the pipe.

30 The joint closing unit incorporates a frame or bracket element 14 secured on the main frame 7 by means of bolts. Idler rollers 15 are journaled on vertically disposed stub shafts 16, one at each side of the tube. These rollers have arcuate tracking grooves fitting against the tube and upper flanges 17. Another roller 18 has an arcuate tracking groove engaging the underside of the pipe or tube. The roller is journaled on a horizontal shaft secured in the bracket 14.

35 A forming disc 19 is journaled in a vertically slidably mounted bearing block 20 engaged upon slideways 21 of the bracket. A vertically disposed screw 22 is screwed through the bracket 14 and has its head 23 loosely disposed in the journal or bearing block. The journal block is fabricated of abutting plates 24, 24 for the purpose of assembly about the head of the screw rod and the ways of the bracket 14. A hand wheel 25 is fixed on the upper end of the screw 45 for manipulation thereof, and a lock nut 26 fixes the screw in position. Rotation of the screw raises and lowers the forming disc relative to the tube and its joint so that the appropriate contact is readily accomplished.

The disc 19 is power driven through a belt 27 engaging a pulley 28 fixed on the end of the shaft 28 which supports the disc. The engagement of the disc with the tube is directly over the joint equally overlapping the adjoining flanges of the tube. A minimum working clearance (see Figure 4) is desirable between the roller flanges 17 and the respective sides of the tube in order that there can be no displacement of the metal of the tube at these points.

The disc is driven at a rate of speed suitable for frictionally inducing forming heat in the metal of the pipe in the adjoining longitudinal edges thereof. These adjoining edges of the tube, as formed up, include longitudinal flanges 29 (see Figure 3). The flanges 29 provide the metal mass to be formed into the joint in the fusing process. The disc driven at a high rate of speed against the flanges 29 heats them and displaces the metal thereof into the crevice 30 between the adjoining edges. The longitudinal margins of the tube become heated and a merging and fusing of all metal flange results. The metal used in the formation of pipe according to this method is preferably malleable which readily heats under the action of the disc.

Having described my invention, I claim:

1. The process of forming pipe comprising the steps of; bending a flat strip into a tubular form with outwardly disposed flanged edges adjacently disposed; passing the tube thus formed along a support in relation to a rapidly rotating disc with the periphery of the disc pressed against the outwardly disposed flanged edges for conjointly heating and pressing the outwardly disposed flanged edges together at the point of contact with the disc causing the metal of these edges to merge thereby forming a completely closed seamless tube.

2. The process of forming pipe comprising the steps of; bending a flat strip into the form of a tube and incidentally forming adjacently disposed flanged edges; passing said tube thus formed along a support; and engaging said flanged edges under considerable pressure with the periphery of a disc rotating at a speed sufficient for producing a softening heat in the flanges by virtue of friction caused by the speed and pressure of the disc, and swaging and merging the heated edges by virtue of the pressure applied as described to form a seamless tube.

WINFORD L. ENGHUSER.
